UNITED STATES PATENT OFFICE.

CLARENCE J. POPE, OF CHICAGO, ILLINOIS, ASSIGNOR OF ONE-HALF TO NELLIE HANSON, OF BATAVIA, ILLINOIS.

MAGAZINE-HAMMER.

1,344,715.

Specification of Letters Patent. Patented June 29, 1920.

Application filed December 29, 1919. Serial No. 348,072.

To all whom it may concern:

Be it known that I, CLARENCE J. POPE, a citizen of the United States, and a resident of the city of Chicago, county of Cook, and 5 State of Illinois, have invented certain new and useful Improvements in Magazine-Hammers, of which the following is a specification.

My invention relates to new and useful 10 improvements in magazine hammers, and has for its object the provision of a magazine hammer which will be durable in structure, economic of manufacture, and highly efficient in use.

Another object is the provision in a 15 magazine hammer of means for feeding the tacks or nails from the magazine to the hammer head.

Another object is the provision in a 20 magazine hammer of means for operating the feeding means simultaneously with the driving of a nail by the driving element.

Other objects will appear hereinafter.

The invention consists in the combinations and arrangements of parts hereinafter described and claimed.

The invention will be best understood by reference to the accompanying drawings forming a part of this specification, and in 30 which,

Figure 1 is a side elevational view of my invention, showing parts in section,

Fig. 2 is a sectional view taken on substantially line 2—2 of Fig. 1,

Fig. 3 is an enlarged view of a portion of Fig. 2,

Fig. 4 is a sectional view of my invention illustrating the feeding mechanism,

Fig. 5 is a side elevational view of 40 another form of my invention, showing parts in section,

Fig. 6 is a sectional view taken on substantially line 6—6 of Fig. 5,

Fig. 7 is a sectional view taken on substantially line 7—7 of Fig. 5, and

Fig. 8 is a sectional view illustrating the feeding mechanism of the form shown in Fig. 5.

The approved form of construction comprises a cylindrical hollow handle 9 secured to one end of which is a suitable cap 10. Rotatably mounted within the member 9 is a magazine 11, which is divided into compartments 12 by means of partitions 13 which project radially inwardly

from the inner surface thereof. The members 13 are provided adjacent their inner ends with an enlarged portion 14, at each side of which is formed a longitudinally extending groove 15. Projecting inwardly 60 from the cap 10 is a tubular member 11, which serves as a bearing in which one end of the shaft 36 is journaled. Mounted upon the opposite end of the member 11 is a cup-shaped housing 17, in which the driving 65 elements and cooperating mechanism are mounted. The driving end of the hammer is divided into two parts, one portion 18 which is mounted upon one end of the magazine 11 and the other portion 19 which is 70 rigidly secured to the housing or casing 17 by any suitable means, preferably by having the member 17 contracted tightly upon it. The member 18 is provided with a recess in which the end of the member 11 75 seats. Positioned upon the member 11 at the end to which the housing 17 is secured is a gland or jam nut 22, which is exteriorly threaded and adapted to thread into the recess 21 formed in the member 18. Slidably 80 mounted within the housing 17 is a weight 23 which is secured to a driving member 24 which serves to drive the tacks or nails used with the device. The member 24 is connected to the member 23 by means 85 of a bolt 25 threaded into a socket formed in the member 24 and into a socket formed in the member 23. A member 25 is provided with a nut 26 by means of which the member 25 may be threaded into the sockets 90 formed into the members 23 and 24, thereby adjusting the relative distance between these two members, the opposite ends of the member 25 being oppositely threaded. Positioned within the housing 17, are spiral 95 springs 27, one end of which is adapted to engage against the lower surface of the member 23, and the opposite end against the upper surface against the member 18, or 19, depending upon which side of the member 100 25 the springs are positioned. Projecting from one side of the member 23 is a lug 28. Slidably mounted in the lug 28 is a rod 29, the lower end of which is pivotally connected to a pawl 30, which is adapted to engage at its lower end with ratchet teeth 31 arranged upon a drum 32, which is rigidly mounted upon the member 11. Mounted upon the member 17, adjacent its lower end 105 is a guide lug 33, through which the member 110

29 is projected. Mounted adjacent the upper end of the member 29 is a collar 34, having a set screw 34' by means of which the member 34 may be adjusted on the rod 5 29 and secured in its positions of adjustment. Positioned upon the rod 29 intermediate the members 34 and 33 and contacting with the members 33 and 34 at its opposite ends is a spiral spring 35.

10 Projecting inwardly from the member 18 is a tubular member 35' in which is journaled one end of the shaft 36. As clearly seen in Fig. 1 and Fig. 5, the shaft 36 is provided with a worm thread. Mounted 15 upon the shaft 36 is a drum or hub 37, radiating from which are spokes or arms 38, so as to form a star wheel. As clearly seen in Fig. 8, the members 38 each project into one of the compartments 12, in which 20 the magazine is divided, the members 18 being spaced apart at their inner ends sufficiently to allow for the passage of the members 38 therein. Mounted upon each of the members 38 is a spiral spring 39 which carries a washer or shoe 39' at its free 25 end which is adapted to abut against the nails or tacks 40 which are used with the device.

30 In operation, the nails or tacks which are intended to be used with the device are inserted in a card board 43 at certain predetermined intervals. The card boards are then inserted into the compartments 12, so that the heads of the tacks or nails engage 35 in the grooves 15. In order to insert the strips of card board or paper which bear the nails or tacks, the cap 10 is removed. After the strips bearing the nails or tacks are inserted into the compartments 12, the 40 star wheel is placed upon the shaft 36 and the shoe or plate 39' on each arm or spoke abuts against the end tack or nail in its respective compartment and tends to force the same outwardly through the forward or 45 driving end of the device. In order to allow for the passage of the tack or nail outwardly through the member 18 so that the tack or nail will be positioned in the space 50, which separates the members 18 and 19, a slot 41 is provided. Upon striking the 55 ends of the members 18 and 19 against an object, the member 23 is carried downwardly by its momentum against the tension of the springs 27, thereby forcing, by means of the member 24, the tack which is 60 positioned in its path downwardly and driving the same into the object upon which the members 18 or 19 have struck. As the member 24 moves downwardly with great rapidity, the paper or card board 43 will be cut off and carried downwardly with the driven tack. The device is so constructed that at 65 the same time the paper strip is severed by means of the member 24, the pawl 30 engages with the teeth 31 and causes the com-

partment 11 to rotate, thereby bringing the next compartment into alignment with the slot 41, so that upon the member 24 resuming its normal position in response to the tension of the springs 27, the tack or nail 70 will be forced from the compartment which is aligned with the slot 41. Inasmuch as the shaft 36 is stationary, the star wheel will be caused to rotate upon the shaft 36, as the magazine 11 rotates. The worm thread 75 upon the shaft 36 is so constructed that the star wheel moves upon the shaft 36, during one rotation of the magazine, a distance equal to the distance between any two of the tacks or nails used in the device, so that 80 the same pressure is always exerted upon the tacks for feeding the same forward. Upon the rebound of the members 24 and 23, the pawl 30 rides over the teeth 31 so that the magazine is not rotated when the driving 85 elements are moving to their normal position.

In the form shown in Fig. 1, I have provided the member 23 with a laterally extending portion 44, which constitutes a rack 90 bar, the same being provided with teeth 45. It is also to be noted that the member 24 is formed integral with the member 23, and no means of adjustment is afforded. Mounted upon a shaft which is rigidly mounted in 95 the housing 17 is a gear wheel 46, which is provided with teeth 48 adapted to mesh with the teeth 45, upon the downward movement of the member 23. As clearly seen in Fig. 3, the gear wheel 46 is formed in the 100 shape of a drum and provided on its inner surface with ratchet teeth 49. Rigidly mounted upon the shaft 47 is a collar 50 projecting from one side of which is a lug 51, to which is pivotally mounted a pawl 52, 105 normally held in engagement with the teeth 49 by means of a spiral spring 53, which abuts against a post 54 mounted upon the member 50. The wheel 46 is loosely mounted upon the shaft 47. Rigidly mounted upon the shaft 47 is a gear wheel 54' which meshes with a gear wheel 55, which is rigidly mounted upon the shaft 56. Suitable bearings 57 for the shaft 56 are mounted upon the housing 17. Mounted upon the lower 110 end of the shaft 56 is a bevel gear 58 which is adapted to mesh with a bevel gear 59, which is rigidly mounted upon a shaft 59'. Rigidly mounted upon the shaft 59' is a 115 drum 60' on the periphery of which is formed gear teeth 60, which are adapted to mesh with teeth 61 formed upon a collar 62, which is rigidly mounted upon the magazine 11.

In operation, the member 23 is moved 120 downwardly through its momentum, as already described, and causes the teeth 45 to come into mesh with the teeth 48 simultaneously with the separation of a tack or nail or the strip in which it is positioned. The 125

wheel 46 is thereby caused to rotate, causing the member 50 to rotate, owing to the engagement of the pawl 52 with the teeth 49. The shaft 56 is thereby rotated through the 5 medium of the bevel gear 55, the bevel gear 54' thereby causing the drum 60' to rotate through the medium of the bevel gear 58 and the bevel gear 59. In this manner, the magazine 11 is rotated through the meshing of the 10 teeth 61 with the teeth 60. A similar slot 41 is provided for the passage of the tacks or nails there-through so as to be positioned in the path of the member 24. The operation of the feeding mechanism is the same as already described, but it is to be noted, as 15 clearly seen in Fig. 4, that the number of compartments is increased, thereby increasing the capacity of the hammer. It is also to be noted that in the form shown in Fig. 1, 20 the tacks are fed from the top of the magazine, whereas in the form shown in Fig. 5, the tacks are fed from the bottom of the magazine.

My magazine hammer is designed primarily for use in tacking up posters and the like where the presence of a strip of paper between the head of the tack and the object nailed or tacked is of little concern. By the use of a hammer such as I have described, 25 the hammer described may be loaded or filled with tacks and used for a considerable length of time without further concern for the tacks. Such a hammer is also useful where the object to be tacked is above the reach of 30 the person and eliminates the necessity of using a magnetized hammer such as is now customarily done.

While I have illustrated and described the preferred form of construction for carrying 40 my invention into effect, this is capable of variation and modification, without departing from the spirit of the invention. I, therefore, do not wish to be limited to the precise details of the construction set forth, 45 but desire to avail myself of such variations and modifications as come within the scope of the appended claims.

Having described my invention, what I claim as new and desire to secure by Letters 50 Patent is:—

1. A magazine hammer comprising a magazine having a plurality of compartments; a hammer head secured to said magazine; means for feeding tacks or nails from 55 said magazine; an inertia-operated driving element slidably mounted in said hammer head; and means operated by said driving element for actuating said feeding means, substantially as described.

60 2. A magazine hammer comprising a magazine having a plurality of compartments therein; means for feeding tacks or nails from said compartments; a hammer head secured to said magazine; a driving 65 element slidably mounted in said hammer

head operable through its momentum upon the striking of a blow by said hammer head; means for actuating said feeding means; and means for restoring said driving element to normal position upon the completion 70 of the actuation of said feeding means, substantially as described.

3. A magazine hammer comprising a magazine having a plurality of compartments therein; a hammer head connected 75 with one end of said magazine; a driving element slidably mounted in said hammer head; means mounted within said magazine for feeding tacks or nails therefrom; and means for actuating said feeding means 80 upon the slideable movement of said driving element in one direction, substantially as described.

4. A magazine hammer comprising a magazine having a plurality of compartments therein; a hammer head secured to one end of said magazine; a driving element slidably mounted in said hammer head; a shaft fixedly mounted and extending centrally longitudinally of said magazine; rotatable means mounted upon said shaft for feeding tacks or nails from said magazine; and means for rotating said rotatable means, 90 substantially as described.

5. A magazine hammer comprising a 95 magazine having a plurality of compartments therein; a hammer secured to one end of said magazine; a driving element slidably mounted in said hammer head; a shaft fixedly mounted and extending longitudinally centrally of said magazine; means rotatably mounted upon said shaft for feeding tacks or nails from said magazine; and means for rotating said feeding means upon the slideable movement of said driving element relatively, in one direction, to said hammer head, substantially as described. 100

6. A magazine hammer comprising a magazine having a plurality of compartments therein; a hammer head secured to 110 one end of said magazine; a driving element slidably mounted in said hammer head; a shaft fixedly mounted and extending longitudinally centrally of said magazine; means rotatably mounted on said shaft for feeding 115 tacks or nails from said magazine; and means operable by said driving element for rotating said feeding means upon said shaft, substantially as described.

7. A magazine hammer comprising a 120 handle; a magazine having a plurality of compartments rotatably mounted within said handle; means mounted within said magazine operable upon the rotation of said magazine for feeding tacks or nails from 125 said magazine; a driving element secured to said magazine; and means operable by said driving element for rotating said magazine, substantially as described.

8. A magazine hammer comprising a 130

handle; a magazine rotatably mounted within said handle; means mounted within said magazine operable upon the rotation of said magazine for feeding tacks or nails from said magazine; a hammer head secured to said magazine; a driving element slidably mounted in said hammer head; and means operable upon the slidable movement of said driving element in one direction, for rotating said magazine, substantially as described.

9. A magazine hammer comprising a handle; a magazine having a plurality of compartments rotatably mounted within said handle; a shaft fixedly mounted and extending centrally longitudinally of said magazine; means for feeding tacks or nails from said magazine rotatably mounted upon said shaft and operable upon the rotation of said magazine; a driving element secured to one end of said magazine; and means actuated upon the slidable movement of said element, in one direction, for rotating said magazine, substantially as described.

25 10. A magazine hammer comprising a magazine having a plurality of compartments

therein; means projecting into each of said compartments for feeding tacks or nails therefrom, said means being operable upon the rotation of said magazine; a driving element secured to said magazine; and means actuated by said driving element for rotating said magazine, substantially as described.

11. A magazine hammer comprising a magazine having a plurality of compartments therein; a shaft fixedly mounted and extending longitudinally centrally of said magazine; a star wheel rotatably mounted upon said shaft; means projecting from said star wheel into each of said compartments for forcing nails or tacks therefrom, upon the rotation of said magazine; and means for rotating said magazine, substantially as described.

In testimony whereof I have signed my name to this specification in the presence of two subscribing witnesses.

CLARENCE J. POPE.
